UNITED STATES PATENT OFFICE

HARRY G. DAY AND WILLIAM E. SKINNER, OF MINNEAPOLIS, MINNESOTA

SMOKE DISPOSAL AND DRAFT INDUCING APPARATUS FOR LOCOMOTIVES

Application filed December 17, 1931. Serial No. 581,688.

This invention relates to a smoke disposal and draft inducing apparatus for locomotives of the type utilized in roundhouses for conducting the products of combustion from the stacks of, and for inducing draft in the furnaces of, locomotives.

An object of the invention is to provide an apparatus of the character mentioned wherein will be incorporated various novel features and characteristics of construction constituting improvements upon certain of the features and characteristics of the smoke disposal and draft inducing apparatus disclosed in our reissue application for patent, Serial Number 566,184, filed September 30, 1931.

Further objects are to equip the up-take pipe or conduit of the apparatus with a cover adapted to be closed at all times when the apparatus is out of use and adapted to be open at all times when a locomotive smoke stack is situated in operative position relatively to the apparatus, the cover being manipulable in substantially the manner as disclosed in our before mentioned application; to equip the apparatus with a valve adapted to close up the passage through the up-take pipe or conduit and open an exhaust passage leading from a locomotive fire box when the exhauster of the apparatus is caused to

function, and to open up the passage through said up-take pipe or conduit and close said exhaust passage when said exhauster is not functioning, in substantially the manner as disclosed in our before mentioned application; to equip the apparatus with an exhauster or portable blower of novel and improved structure adapted to be moved from place to place about the roundhouse to be selectively associatable with the up-take pipe or conduit of any one of a plurality of different smoke disposal and draft inducing apparatuses, and to provide improved means for transporting said exhauster or portable blower about a roundhouse, along the roof or top thereof as disclosed; to equip the apparatus with a novel and improved raising and lowering mechanism adapted to be automatically actuated to associate or assemble the up-take pipe or conduit of the apparatus with, and to remove said up-take pipe or conduit from, the

smoke stack of a locomotive; to so construct said novel and improved raising and lowering mechanism that it can be actuated by the smoke stack of the locomotive; to provide in the apparatus an improved arrangement adapted to care for variations in the heights of locomotive smoke stacks, and an improved arrangement adapted to care for variations from the vertical as may be caused, for example, by a broken spring; and to provide in the apparatus an improved arrangement permitting a locomotive smoke stack to be in communication with the up-take pipe or conduit of the apparatus at variable locations in the vicinity of the apparatus, making it possible to move a locomotive backwardly or forwardly within limits while being fired, or while a fire exists in the fire box, without emitting smoke or gases into a roundhouse.

Other objects and advantages of the invention will become apparent from the full description thereof now to be made, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is an elevational view, partially in section and partially broken away, of an apparatus in which the features of the invention are incorporated, disclosing said apparatus applied to use;

Fig. 2 is an enlarged vertical sectional view of the up-take pipe and the exhauster or portable blower of the apparatus taken substantially as on line 2—2 in Fig. 4;

Fig. 3 is a vertical sectional view taken as on line 3—3 in Fig. 2;

Fig. 4 is a vertical sectional view taken substantially as on line 4—4 in Fig. 2;

Fig. 5 is an enlarged horizontal sectional view taken substantially as on line 5—5 in Fig. 4;

Fig. 6 is an enlarged horizontal sectional view taken substantially as on line 6—6 in Fig. 4; and

Fig. 7 is an enlarged horizontal sectional view taken substantially as on line 7—7 in Fig. 4.

With respect to the drawings and the numerals of reference thereon, 10 designates the roof of a roundhouse which may have engine stalls in any desired number, 11 represents columns between the stalls, and 12 indicates a locomotive upon a track 13 and within a stall.

A separate smoke-disposal and draft-inducing apparatus, denoted generally at 14, may be provided for each stall.

An up-take pipe or conduit 15 of the apparatus 14 may consist of an upper barrel 16, suitably supported upon the roundhouse roof, as by a closure hood 17 surrounding said barrel 16 and an opening 18 in said roof through which the lower end portion of the barrel 16 projects, an intermediate barrel 19 having its upper end portion pivotally supported within the lower end portion of the barrel 16, as at 20, and a lower barrel 21 having its upper end portion telescopingly received in the lower end portion of the barrel 19, as at 22.

The pivotal arrangement between the upper barrel 16 and the intermediate barrel 19 is such that the barrels 19 and 21 can swing as a unit longitudinally of the track 13, and the barrel 19 includes elongated slots 23 in its opposite walls receiving the pivot pin 20 to allow for slight sidewise swinging movement of the intermediate and lower barrels, as, for example, to accommodate the up-take conduit to a locomotive smoke stack which may not be exactly vertical, as will be understood. As shown more clearly in Fig. 2, the upper end 24 of the intermediate barrel 19 desirably snugly engages the inner wall of the belled portion of the upper barrel 16 to provide a slidable, preferably close fit between the barrels 16 and 19 no matter what may be their relative positions.

A counterweight 25, suspended from a cord 26 which rides over fixed pulleys 27 and is attached to the barrel 21, as at 28, is for the purpose of counterbalancing the lower barrel, and the telescoping barrels are equipped with mechanism adapted to prevent binding which might otherwise be caused when the pull of the counterweight and the lifting movement of a locomotive stack upon the lower telescoping barrel are unequal. As disclosed, guide slats 29 are secured upon the outer surface of the barrel 21 in diametrically opposed relation to each other, said guide slats extending lengthwise of said barrel 21 and preferably lying in a plane which extends substantially longitudinally of the track 13, and brackets 30, secured upon the barrel 19 as at 31, support guide rollers 32, two for each guide slat, having flanges 33, which pass through openings in the barrel 19 and engage the opposite sides of said guide

slats, said guide rollers being mounted in said brackets as denoted at 34. A packing 35 between the intermediate barrel 19 and the lower barrel 21 may be of any preferred design and construction.

A raising and lowering mechanism of the apparatus, represented generally at 36, is adapted to be actuated by the smoke stack of a locomotive to associate the up-take pipe or conduit 15 with said smoke stack and to remove said up-take pipe or conduit from the smoke stack. Of said raising and lowering mechanism, 37 designates spaced apart suspension slabs upon the roundhouse structure suitably supporting upper and lower, horizontal cross shafts, indicated 38 and 39, respectively, and 40 denotes a raising and lowering bar extending substantially longitudinally of the track 13, the rearward end portion of said bar 40 being freely received between said suspension slabs and said horizontal cross shafts in such manner that the bar can have upward and downward swinging movement, as well as longitudinal sliding movement, but can have very little lateral or sidewise movement. The forward end portion of the bar 40 is rigidly attached, as at 41, to a yoke 42, which yoke in turn rigidly supports a funnel shape member 43 extending upwardly from the bar 40 and pivotally supported within the lower end portion of the barrel 21, as at 44. The pivotal arrangement between the lower barrel 21 and the funnel shape member 43 is such that said funnel shape member 43 can swing longitudinally of the track 13, and the funnel shape member includes elongated slots 45 in its opposite walls receiving the pivot pin 44 to allow for slight sidewise swinging movement of said funnel shape member to better accommodate the up-take conduit to a locomotive smoke stack which may not be exactly vertical. The lower portion 46 of the funnel shape member 43 is of configuration best suited to the reception of a locomotive smoke stack which is adapted to positively enter said portion 46, and said portion 46 is cut away at one of its sides, as shown at 47, adjacent the bar 40, to allow entry of a smoke stack into said portion 46. Also, the portions of the yoke 42 and the member 43 at the general location of the cut-away portion 47 are obliquely disposed relatively to the body of the bar 40, slanting upwardly of said bar and inwardly of the up-take pipe or conduit, as represented at 48. As shown more clearly in Fig. 2, the upper end 49 of the funnel shape member 43 desirably snugly engages the inner wall of a belled portion of the lower barrel 21 to provide a slidable, preferably close fit between said member 43 and said barrel 21 no matter what may be their relative positions. Means for adjustably limiting downward movement of the lower barrel 21 in the intermediate barrel 19 may consist of rods 50 suit-

ably secured to the yoke 42 at location adjacent the funnel shape member 43, as at 51, passing upwardly through ears 52 upon a flange 53 set at the lower end of the barrel 19, and carrying nuts or collars 54 situated to engage the upper surfaces of said ears, each said nut or collar receiving a set screw 55 for locking the nut or collar at any preferred location along the length of the corresponding rod.

10 A counterweight 56, suspended from a cord 57 which rides over fixed pulleys 58 and is attached to the bar 40 as at 59, is for the purposes of counterbalancing said bar 40 and of 15 normally situating said bar and the funnel shape member 43 at about the dotted line position disclosed in Fig. 1.

15 A cover 60 for the upper end of the up-take pipe or conduit is adapted to be closed at 20 all times when the apparatus is out of use and is adapted to be open at all times when a locomotive smoke stack is situated in operative position relatively to the apparatus. As disclosed, the cover 60 is pivoted upon the 25 upper portion of the barrel 16 as at 61, and includes a protruding arm 62 carrying a weight 63 of sufficient magnitude to move said cover to open position. A cord or wire 64 attached to the cover at the side of its pivot 30 opposite the weight is also attached to the end portion of the cord 26 which is adjacent to the barrel 21, the arrangement being such that when said barrel 21 is moved to its lowermost position by its own weight and the 35 weight of the bar 40, the cord or wire 64 is drawn downwardly to move the cover to closed position against the action of the weight 63, but when the barrel 21 is elevated, said weight acts to open the cover. Means 40 may be provided for closing the cover even when a smoke stack is associated with the up-take pipe or conduit.

45 An exhauster for the up-take pipe or conduit 15 may consist of a usual or preferred type of fan 65 actuated by a suitable motor 66, both shown situated upon the roundhouse roof. As disclosed, the upper barrel 16 has an opening 67 receiving one end of a box 68 the opposite end of which communicates 50 with the interior of the fan housing 69. Numeral 70 represents the fan housing outlet.

55 A valve 71 is for the purpose of closing up the passage through the up-take pipe or conduit and of opening an exhaust passage 72, leading from a locomotive fire box and through the exhauster, when the motor 66 is operated to actuate said exhauster, said valve 71 being adapted to open up the passage through said uptake pipe or conduit and to 60 close said exhaust passage when said exhauster is not functioning. As disclosed, the valve 71 is pivoted in the barrel 16 at a location intermediate the ends of said valve, as indicated at 73, and includes an arm 74 for 65 closing the passage through the barrel 16

and an arm 75 for closing the passage through the box 68, one of said arms being in open position while the other arm is in closed position. The arm 75 is constructed to be heavier than the arm 74, so that normally 70 the passage through the box 68 is closed and the passage through the barrel 16 is open. The arrangement is such, however, that when the fan 65 is operated, suction created in the box 68 is sufficient to draw the arm 75 to 75 about the position as disclosed in full lines in Fig. 2, to thus open the passage through said box and close the passage through the barrel 16, as will be obvious.

80 The box 68 and the fan housing 69 are not permanently connected together, but the arrangement is such that the exhauster or portable blower can be moved from place to place about the roundhouse, to be selectively 85 associatable with the up-take pipe or conduit of any one of a plurality of different smoke disposal and draft inducing apparatuses, and means is provided for transporting the exhauster or portable blower about a roundhouse, along the top thereof as disclosed, to 90 position adjacent any one of a plurality of different smoke disposal and draft inducing apparatuses thereof and in smoke-tight relation to the box 68, or equivalent, of the corresponding apparatus.

95 As shown more clearly in Figs. 1, 2 and 3, the fan housing 69 includes a tubular inlet 76 the outer end of which, adjacent the boxes 68 of the different apparatuses, desirably integrally supports an outwardly extending 100 annular flange 77, which annular flange 77 is as shown perpendicular to said tubular inlet 76. The arrangement is such that when the fan housing 69 is positioned adjacent a box 68, about as shown in Fig. 2, the tubular inlet 76 and the exhaust passage 72 of the corresponding box 68 will align. The tubular inlet 76 telescopically receives a tubular fitting 78, which fitting is slidably, but desirably snugly, arranged in the outer end portion of said tubular inlet 76, and extends outwardly of the exhauster or portable blower in direction toward the several smoke disposal and draft inducing apparatuses of a roundhouse. When the parts are positioned 105 as in Figs. 1, 2 and 3, the tubular fitting 78 aligns with the tubular inlet 76 and the exhaust passage 72, being disposed between said tubular inlet and exhaust passage.

110 The outer end of the box 68 of each apparatus of the invention desirably integrally supports an outwardly extending annular flange 79, which annular flange 79, is as shown arranged approximately perpendicularly to the outer end portion of the corresponding box 68, but has its marginal portion 80 bent in curvilinear manner in direction toward the corresponding up-take pipe or conduit. Also, the outer end of the tubular fitting 78 of the exhauster or portable 115

blower desirably integrally supports an outwardly extending annular flange 81, which annular flange 81 is as shown arranged approximately perpendicularly to the outer end portion of said tubular fitting 78, but has its marginal portion 82 bent in curvilinear manner in direction toward the exhauster or portable blower. At location where the tubular fitting 78 meets the box 68, said fitting and box are shaped so that the outer ends of the fitting and box are somewhat nested, the one within the other as shown more clearly in Fig. 2. The annular flange 81 upon the tubular fitting 78 fixedly carries small bolts 83 spaced apart about the circumference of said annular flange 81 and extending inwardly of the exhauster or blower and passing through openings spaced apart about the circumference of the annular flange 77 upon the tubular inlet 76. Coil springs 84, one upon each bolt 83 and between the annular flanges 77 and 81, urge the tubular fitting 78 outwardly of the tubular inlet 76, and nuts 85, one adjustably arranged upon each bolt 83, normally engage the inner surface of the annular flange 77 to limit outward movement of said tubular fitting 78. See Fig. 2.

Of the means for transporting the exhauster or blower about a roundhouse, from stall to stall thereof, 86 represents a track which is shown in Figs. 1, 2 and 3 as parallel to a series of the apparatuses of the invention arranged in alinement with each other, in spaced relation to the boxes 68 of said apparatuses, the outer ends of all of said boxes also being arranged in alinement and parallel to said track 86. Spaced wheels 87 carrying the exhauster or portable blower are firmly mounted upon said track 86, and cords or cables, designated 88 and 89, respectively, arranged parallel to a vertical plane disposed longitudinally of the track 86, extend in opposite directions from said exhauster or portable blower and are attached thereto as at 90 and 91. The cord or cable 88 passes over a pulley 92, disclosed as at one end of the roundhouse, to a motor 93, or the like, at this same end of said roundhouse, and the cord or cable 89 passes over a pulley 94, disclosed as at the opposite end of the roundhouse, to a motor 95, or the like, at said opposite end of the roundhouse, the motors 93 and 95 obviously being for the purpose of actuating the cords or cables 88 and 89 over the pulleys to aline the exhauster or portable blower with any desired one of the apparatuses of the invention, there being three of said apparatuses accounted for in Fig. 3 of the drawings, although a single exhauster or portable blower could serve for a greater or a less number of apparatuses. Any other suitable arrangement for transporting the exhauster or portable blower along the track 86 can be substituted for the arrangement as illustrated and described.

When the exhauster or portable blower approaches the box 68 of an apparatus with which said exhauster or portable blower is at a particular time to be associated, the lip or reversely bent portion 82 of the annular flange 81 upon the tubular fitting 78 of said exhauster or blower guides said tubular fitting past the lip or reversely bent portion 80 of the annular flange 79 upon the box 68. As the exhauster or portable blower moves farther along, said annular flange 81 rides over the annular flange 79, this causing the coil springs 84 to be compressed somewhat, and eventually the outer end of the box 68 is seated into the outer end of the tubular fitting 78 when said tubular fitting reaches the appropriate position, as the parts are shown in Fig. 2, said box 68 and tubular fitting 78 being positively assembled with each other at this time in smoke-tight fashion. Evidently, upon actuation of either motor 93 or 95, to move the exhauster or portable blower along the track 86, in either direction from the position as shown in the drawings, the coil springs 84 are compressed during the first part of the movement to allow the annular flange 81 to slide over the annular flange 79 until said flanges eventually clear each other. It should be remarked that the nuts 85 are positioned to limit outward movement by the coil springs 84 of the tubular fitting 78 and its annular flange 81 at location short of the position which would preclude clearance for the lip or reversely bent portion 82 when this passes the lips or reversely bent portions 80 of the annular flanges 79 upon the boxes 68 of the different apparatuses in a roundhouse.

Supposing the bar 40 to be in normal position, say, for example, as disclosed in dotted lines in Fig. 1, and it is desired to associate a locomotive smoke stack with the lower portion 46 of the funnel shape member 43 of the up-take pipe or conduit 15, all that is necessary to be done to accomplish this result is to move the locomotive from the dotted line position of the smoke stack in said Fig. 1 toward the full line position of the locomotive disclosed, until said smoke stack has caused the bar 40, together with the member 43 and the lower barrel 21, to be elevated, and has entered the portion 46 of said funnel shape member. The arrangement is such that the smoke stack will snugly fit into the portion 46 of the member 43 when at any one of several different positions to provide a smoke-tight association between said stack and the up-take pipe or conduit, as will be understood. After the smoke stack has associated itself with the portion 46 of the member 43 of the up-take pipe or conduit, movement of said smoke stack still farther ahead will obviously cause the member 43 and the barrel 21 and the bar 40 to be still farther elevated and said bar 40 to be slid longitudinally ahead. Upon return movement of the loco-

6 motive, the smoke stack will not be removed from the up-take pipe or conduit until the rearward position at which the smoke stack entered the portion 46 has been passed, so that a locomotive can be moved forwardly and 70 backwardly within limits while associated with the up-take pipe or conduit of the apparatus without permitting smoke or gases to be emitted into a roundhouse. See the dotted 75 line positions of the lower barrel 21 and the member 43 in both Figs. 1 and 2.

8 The utilization of the improved raising and lowering mechanism actuated by the smoke 80 stack of a locomotive to associate the up-take 85 pipe with, and to disassociate said up-take pipe from, said smoke stack, eliminates all labor and maintenance which have heretofore been required to accomplish the association 90 and disassociation of stacks with apparatuses of the present character, and the arrangement as disclosed obviously makes provision for variations in the heights of locomotive smoke stacks, as well as for variations from the vertical as may be caused by broken springs. 95 See both the joint at 20 and the joint at 44.

10 As will be evident, whenever the bar 40 and the member 43 and the barrel 21 are elevated by a smoke stack, the cover 53 will be in open position, and when said bar and member 15 and barrel are allowed to lower, said cover will be closed.

15 Obviously, when there is no exhauster or blower at the box 68 of an apparatus, the arm 75 of the corresponding valve 71 will be positioned to close the exhaust passage 72, and the arm 74 of said valve 71 will be positioned to cause the upper barrel 16 to be open at the location of the valve. In fact, the only time the valve 71 of an apparatus is positioned as 20 in full lines in Fig. 2, is when the exhauster or blower is in operative relation to said apparatus and the fan thereof is exhausting from the exhaust passage 72, as is the case in said Fig. 2.

25 What we claim is:

1. In an apparatus of the character described, an up-take conduit including a movable lower pipe, a member pivotally mounted upon a lower portion of said lower pipe and 50 adapted to be associated with the smoke stack of a locomotive, and means adapted to be actuated responsively to the approach of a locomotive for assembling said member and said smoke stack with each other.

55 2. In an apparatus of the character described, an up-take conduit including a swingable and vertically movable lower pipe, a member pivotally mounted upon a lower portion of said lower pipe and adapted to be associated with the smoke stack of a locomotive, and means adapted to be actuated responsively to the approach of a locomotive for causing said smoke stack to be assembled 60 with said member.

65 3. In an apparatus of the character de-

scribed, an up-take conduit including a movable lower pipe, a member pivotally supported by said lower pipe and adapted to be associated with the smoke stack of a locomotive, and means adapted to be actuated 70 responsively to the approach of a locomotive for causing said smoke stack to enter the mouth of said member, said smoke stack and member being adapted to become automatically disassembled upon the departure 75 of said locomotive away from the vicinity of said up-take conduit.

4. In an apparatus of the character described, an up-take conduit including a movable lower pipe, a member pivotally mounted 80 upon said lower pipe and adapted to be associated with the smoke stack of a locomotive, means adapted to be actuated responsively to the approach of a locomotive 85 to situate said member at position to be entered by said smoke stack, a cover for said up-take conduit, means for normally maintaining said cover in closed position, and means for maintaining said cover in open position when said member is in position 90 to be entered by said smoke stack.

5. In an apparatus of the character described, an up-take conduit comprising a plurality of pipes arranged to have movement 95 relatively to each other, including a lower pipe, a member pivotally supported upon said lower pipe and adapted to be associated with the smoke stack of a locomotive, said up-take conduit also including an upper pipe with which said lower pipe communicates 100 to carry products of combustion away from said smoke stack, means adapted to be actuated responsively to the approach of a locomotive to situate said member at position 105 to be entered by said smoke stack, a cover for said upper pipe, means connecting said cover with said lower pipe for normally maintaining the cover in closed position, and means for maintaining said cover in open position when said member is in position 110 to be entered by said smoke stack.

6. In an apparatus of the character described, an up-take conduit mounted above rails adapted to carry a locomotive, said up-take conduit including a lower pipe mounted 115 to swing longitudinally of said rails and to be capable of having a raising and a lowering movement, a member pivotally mounted upon said lower pipe to swing longitudinally of said rails, and means responsive to the approach of a locomotive to situate said member at position to be entered by the smoke stack of said locomotive.

7. In an apparatus of the character described, an up-take conduit including a lower pipe mounted to swing relatively to a smoke stack and to be capable of having a raising and a lowering movement, a tubular member pivotally mounted in the lower portion of said lower pipe to swing relatively 125 130

to a smoke stack in the same direction as said lower pipe, and means responsive to the approach of a locomotive to situate said member at position to be entered by the smoke stack of a locomotive.

8. In an apparatus of the character described, an up-take conduit mounted above rails adapted to carry a locomotive, said up-take conduit including a lower pipe mounted to swing longitudinally of said rails and to be capable of having a raising and a lowering movement, a member pivotally supported by said lower pipe, and means attached to said member and responsive to the approach of a locomotive to situate the member at position to be entered by the smoke stack of said locomotive, both said lower pipe and said member being adapted to have upward and downward swinging movement and movement in the direction of travel of said smoke stack while said smoke stack is associated with said member.

9. In an apparatus of the character described, an up-take conduit mounted above rails adapted to carry a locomotive, said up-take conduit including a lower pipe mounted to swing longitudinally of said rails and to be capable of having a raising, a lowering, and a slight sidewise movement, a member supported by said lower pipe and also adapted to have a raising, a lowering, and a slight sidewise movement, and means adapted to be actuated responsively to the approach of a locomotive to situate said member at position to be entered by the smoke stack of said locomotive.

10. In an apparatus of the character described, an up-take conduit mounted above rails adapted to carry a locomotive, said up-take conduit including a lower pipe, a member mounted upon said lower pipe to swing longitudinally of said rails and to be capable of having a slight sidewise movement, and means adapted to be actuated responsively to the approach of a locomotive to situate said member at position to be entered by the smoke stack of said locomotive.

11. In an apparatus of the character described, an up-take conduit comprising a plurality of pipes arranged to have movement relatively to each other, including a lower pipe, a member pivotally mounted upon said lower pipe and adapted to be associated with the smoke stack of a locomotive, said up-take conduit also including an upper pipe with which said lower pipe communicates to carry products of combustion away from said smoke stack, a portion of said member being normally situated below the elevation of the upper portion of said smoke stack, and a member mounted for swinging and longitudinal movement and rigidly connected to said pivoted member adapted to be elevated by said smoke stack

to situate said pivoted member at position to be entered by the smoke stack.

12. In an apparatus of the character described, an up-take conduit comprising a plurality of pipes, including an upper pipe, an intermediate pipe pivotally supported upon said upper pipe, and a lower pipe, a tubular member pivotally supported upon said lower pipe and adapted to be associated with the smoke stack of a locomotive, said intermediate and lower pipes and said tubular member being mounted to swing in the general direction of the length of said locomotive, and said lower pipe being arranged in sliding, telescoping relation to said intermediate pipe, and a portion of said tubular member being normally situated below the elevation of the upper portion of said smoke stack, and a member rigidly connected to said pivoted tubular member and mounted to slide in the direction of movement of the smoke stack and adapted to be elevated by said smoke stack as the same advances toward said pivoted tubular member, whereby to associate the mouth of said pivoted tubular member with a locomotive smoke stack.

13. In an apparatus of the character described, an uptake conduit mounted above rails adapted to carry a locomotive, said up-take conduit including a lower pipe mounted to swing longitudinally of said rails and to be capable of having a raising and a lowering movement, a member pivotally supported upon the lower portion of said lower pipe, and means attached to said pivoted member and adapted to be engaged by the smoke stack of an advancing locomotive to situate the mouth of said pivoted member at position to be entered by the smoke stack.

14. The combination as specified in claim 13, said lower pipe and pivoted member and said means being adapted to have upward and downward swinging movement and movement in the direction of travel of the smoke stack while said smoke stack is associated with said pivoted member.

15. The combination as specified in claim 2, said pivoted member being adapted to have upward and downward swinging movement in the direction of travel of the smoke stack while said smoke stack is associated with said pivoted member.

16. In combination, a plurality of spaced apart smoke disposal and draft inducing apparatuses for locomotives, each of said apparatuses including an exhaust passage, and a portable exhauster adapted to be selectively assembled with the exhaust passage of any one of said apparatuses.

17. In combination, a plurality of spaced apart smoke disposal and draft inducing apparatuses for locomotives, each of said apparatuses including an exhaust passage arranged above the roof of a roundhouse, a

portable exhauster adapted to travel along said roundhouse roof, and means for causing said portable exhauster to be selectively associated with any desired one of said exhaust passages.

18. In combination, a plurality of spaced apart smoke disposal and draft inducing apparatuses for locomotives, each of said apparatuses including an exhaust passage, a portable exhauster adapted to be selectively associated with any desired one of said exhaust passages, a track for said portable exhauster, and means for propelling said portable exhauster along said track to positions adjacent said exhaust passages, respectively.
19. In an apparatus of the character described, an up-take conduit including an exhaust passage, a portable exhauster adapted to travel transversely of said passage, and means for automatically connecting up said portable exhauster and said exhaust passage with each other and for allowing said exhauster and passage to become automatically disassociated.
20. The combination as specified in claim 19, wherein said portable exhauster includes a tubular inlet, a tubular fitting telescopically arranged within said tubular inlet and projecting therefrom, said tubular inlet and said tubular fitting each having outwardly extending flanges, means resiliently urging the flanges of said tubular inlet and said tubular fitting apart, and means limiting the extent to which said tubular fitting can move outwardly of said portable exhauster, and wherein said exhaust passage includes an outwardly extending flange adapted to be resiliently engaged by the flange of said tubular fitting, the flanges of said tubular fitting and of said exhaust passage, respectively, being bent in direction away from each other at the outer margins of said flanges, whereby said exhaust passage and said tubular fitting can be assembled together by movement of said portable exhauster transversely of said exhaust passage.
